CLAIM

The ornamental design for a mixer, as shown and described.

DESCRIPTION

FIG. 1 is a front perspective view of a mixer showing the new design;

FIG. 2 is a top plan view thereof;

FIG. 3 is a left side view thereof; and

FIG. 4 is a right side view thereof.

FIG. 5 is a front perspective view of the mixer shown in FIG. 1 with a retainer element affixed to the top of the mixer; and, FIG. 6 is a front perspective view of the mixer shown in FIG. 5 having an embodiment of a thermoblock installed in the retainer element.

In the drawings, the broken lines are for the purpose of illustrating environment only and form no part of the claimed design.
